ATTORNEY.

UNITED STATES PATENT OFFICE.

JOHN LA RUE ROBINSON, OF RENO, NEVADA, ASSIGNOR TO RENO OPTICAL COMPANY,
OF RENO, NEVADA, A CORPORATION OF NEVADA.

HEATER.

1,406,900.

Specification of Letters Patent. Patented Feb. 14, 1922.

Application filed June 18, 1920. Serial No. 389,289.

To all whom it may concern:

Be it known that I, JOHN LA RUE ROBINSON, a citizen of the United States, residing at Reno, in the county of Washoe and State 5 of Nevada, have invented certain new and useful Improvements in Heaters; and I do hereby declare the following to be a full, clear, and exact description of the invention, such as will enable others skilled in the 10 art to which it appertains to make and use the same.

This invention relates to heating pads adapted to be applied to areas of the body and to be used for warming and curative 15 purposes and it consists in the novel features hereinafter described and claimed.

An object of the invention is to provide a heating pad of the character stated which is of simple and durable structure and which 20 has its parts so arranged that they are not liable of becoming disarranged when the device is applied and consequently the heating pad is a safe medium which may be used by those, practically inexperienced, and 25 without danger of burning the person to which the pad is applied.

With this object in view, the pad comprises a metallic casing which is convexo-concave in transverse section and circular in 30 plan.

A resistance element is located in the heater body and is connected with conducting wires which in turn may be connected in any suitable manner with a source of 35 electrical supply, preferably of a voltage not to exceed 110. At the point where the wires pass through the side of the heater body, they are surrounded by a coil of wire which is attached to the heater body and this coil 40 prevents the insulation of the conductor wires from cutting and causing short circuit. A heat resisting mat is located in the heater body at the outer side thereof and is designed to prevent the heat from passing 45 through or radiating from the outer side of the heater body and consequently the heat in emerging from the heater body must pass through the inner side thereof and toward the portion of the heater body of the wearer 50 to which the device is applied. An envelope of special design is provided to receive the heater body, and the said envelope is preferably made of canton flannel and is provided

with a tape for closing the flaps thereof and securing them in a closed position. 55

In the accompanying drawings:

Figure 1 is a plan view of the complete pad,

Figure 2 is a similar view of the heater thereof, 60

Figure 3 is a similar view of the electric current conducting means of the heater,

Figure 4 is a perspective view of the parts, separated, which form the heating body,

Figure 5 is a plan view of the envelope. 65

Figure 6 is a cross-sectional view of the heater pad or body.

Figure 7 is a cross-sectional view of the envelope to contain the heater pad.

Figures 8 and 9, respectively, are plan 70 and cross-sectional views of a base or support for the heater, and

Figures 10 and 11, respectively, are longitudinal and transverse sectional views of the radiator or resistance element employed. 75

As illustrated in the accompanying drawings, the heating pad comprises a body composed of an inner plate 2 and an outer plate 3. These plates are secured together at their edges and the plates are circular in plan 80 and convexo-concave in transverse section.

A resistance element 4 is located in the body 1 between the plates 2 and 3 thereof and approximately at the center of the body. This resistance element is of usual form and 85 may consist of a tubular body of clay or other material enclosing a wire having resistance characteristics or features. Current wires 5 pass through the plate 3 and are connected with the resistance element 4 90 in a usual manner. These wires connect at their outer ends with a plug 6 which may be screwed into the socket of an electric fixture and whereby the current may be supplied to the resistance element when the device is applied and in use. A heat resisting material 7 is located in the body 1 adjacent the inner surface of the plate 3 and between the plate 3 and the resistance element and this heat resisting material is 100 adapted to prevent heat from passing out of the body to any great extent, through the plate 3 and directs the heat toward the plate 2 through which it eventually passes out of the body 1. A wire coil 8 is attached to the 105 plate 3 and surrounds the wires 5 in the

vicinity of the plate and prevents the edges of the openings in the plate 3 through which the wires 5 pass from cutting the insulation of the wires and thereby causing short circuit.

In conjunction with the heating apparatus hereinbefore described, an envelope is used for receiving the same when the device is applied to a person and the said envelope 10 will now be described. The envelope comprises an inner side portion 9 preferably of canton flannel and which is circular in plan. The envelope also includes flap portions 10 which are sewed at their outer edges to the 15 edge of the portion 9 and the inner parts of the flaps 10 overlap each other thereby providing half pockets at the side portions of the part 9 and the pockets may receive the circular body 1. Tapes 11 are sewed to the 20 inner parts of the flaps 10 and one of the tapes may extend through a slot 12 provided in one of the flaps whereby the edge portions of the flaps may lie snugly against each other, and the tapes may be carried 25 around the front or outer surface of the part 9 and secured together by tying or any other suitable means.

When the parts are assembled as indicated, the heating pad may be applied to any 30 point of the body and when the electric current is turned on the heat which is generated at the resistance element 4 radiates from the same and passes through the inner side of the body 1 and the flaps of the envelope and 35 comes in contact with the portion of the body of the user to which the device is applied.

In some instances it may be desirable to use the heater for warming fluids, as for in-

stance, milk or foods to be given infants, 40 or invalids, and in this event a stool 14 having a concaved upper surface is provided and the said stool is placed upon a table top or other support and the body 1 in an inverted position is placed upon the stool. 45 The vessel containing the food or material to be heated is placed upon the upper surface of the plate 2 and when the current is turned on and the heat generated, the said fluid or material will be heated in a manner 50 which is apparent.

Having described the invention, what is claimed is:—

1. A heater pad for local application comprising separable sections, heating means intermediate the sections, and means associated with one section to direct and confine the heat to the other section. 55

2. A heater pad for local application comprising separable sections, heating means intermediate the sections, and means associated with one section to direct and confine the heat to the other section, and to this end being substantially concaved opposite the other section, and heat insulating means 65 in the concavity.

3. An envelope of the class described having overlapping closure portions, one of said portions having an opening at a distance from its free edge, a fastening element extending from the other portion through the opening to effect a substantially flat closure. 70

In testimony whereof I affix my signature in presence of a witness.

JOHN LA RUE ROBINSON.

Witness:

MARY CAPEZZOLI.
